(57) **CLAIM**

We claim the ornamental design for a hydroponic container, as shown and described.

DESCRIPTION

FIG. 1 is a front perspective view showing the new design; FIG. 2 is a front view thereof; FIG. 3 is a rear view thereof; FIG. 4 is a left side view thereof; FIG. 5 is a right side view thereof; FIG. 6 is a top view thereof; and, FIG. 7 is a bottom view thereof.

The broken lines in the figures depict portions of the hydroponic container that form no part of the claimed design.

1 Claim, 7 Drawing Sheets
